UNITED STATES PATENT OFFICE.

CHARLES L. COURSON, OF PITCAIRN, PENNSYLVANIA.

UNCOUPLING MECHANISM FOR PIPE-COUPINGS.

968,131.

Specification of Letters Patent. Patented Aug. 23, 1910.

Application filed April 1, 1910. Serial No. 552,874.

To all whom it may concern:

Be it known that I, CHARLES L. COURSON, a citizen of the United States, residing at Pitcairn, in the county of Allegheny and State of Pennsylvania, have invented certain new and useful Improvements in Uncoupling Mechanism for Pipe-Couplings, of which the following is a specification, reference being had thereto to the accompanying drawing.

My invention consists of an improvement in means for uncoupling the hose terminals of air brake or other pipe connections, and is designed to provide a device by which the uncoupling may be effected by an operator located on the car platform, avoiding the necessity of going between the cars.

The invention consists of a lever secured to the hose with such relation to the coupler terminal, that the lifting of the lever will effect relative rotation and separation of the coupler terminals.

In the drawings:—Figure 1 is a view of the device in elevation at the end of a car. Figs. 2 and 3 are perspective views of the operating lever, showing different arrangements of clamping constructions. Fig. 4 is a diagram showing the hose terminals coupled. Fig. 5 is a similar view illustrating the uncoupling operation.

The hose terminals 2, 2, of air brake or steam systems are ordinarily coupled by a well known type of coupler 3 in which interfitting disk-like heads with interengaging 35 lugs and housings of segmental form, are locked and unlocked by a partial rotation of either head with relation to the other. Ordinarily this is done by hand and is accompanied with danger to the operator from 40 getting between the cars.

In carrying out my invention, I provide a lever arm 4 which has a clamp terminal 5 at one end of any suitable kind and an eye 6 or other connecting element for a lifting 5 chain 7 at the other end. The lever is firmly secured backwardly from the coupler head 3 by a companion clamp 8 and bolts as in Fig. 2, or by a tongue 9 and eye 10 and a bolt as in Fig. 3, although any suitable 50 clamping device may be used. The arm 4, being thus firmly secured to the hose, extends outwardly along above the hose, parallel with its general direction, and terminates

by its eye 6 immediately above the center of the coupler heads, as clearly shown in Fig. 5. By this arrangement, when the chain 7 is lifted, preferably by an inserted ring 11, the coupler heads are thrust upwardly as in Fig. 5, the hose sections bending abruptly, due to their stiff character and weight, so that the angle of each hose section with its coupler head is altered to the position shown in Fig. 5, each head rotating on the other sufficiently to effect separation.

The efficiency of the device depends largely on the arrangement of the lever arm 4 with relation to the hose and its coupler head as above described.

What I claim is:—

1. Uncoupling mechanism for the joint of a fluid-pressure line consisting of a clamp having a lever arm extending over the coupling and provided with an operating connection, substantially as set forth.

2. The combination with the hose terminal of a fluid circulation pipe adapted for uncoupling by rotation, of a clamp engaging the coupling and provided with a lever extension projecting over the coupling to effect upward lifting and rotation of the coupling with relation to a companion coupling.

3. The combination with the depending terminal of a hose and its coupling head, of an L shaped lever secured to the hose and extending over the coupling head, substantially as set forth.

4. The combination with the depending terminal of a hose and its coupling head, of an L shaped lever secured to the hose and extending over the coupling head, and a flexible lifting connection for operating the lever from above, substantially as set forth.

5. A lever for the purpose described composed of semi-circular clamps having terminal connecting flanges, one of said clamps having a lever arm extending beyond and forming a continuation of one of its flanges, bent in the general direction of the plane of said flange, and provided with a terminal eye.

In testimony whereof I affix my signature in presence of two witnesses.

CHARLES L. COURSON.
